JOURNAL BOX CONSTRUCTION

Homer L. Hexamer, Canton, Ohio, assignor to
The Timken Roller Bearing Company, Canton, Ohio, a corporation of Ohio

Application November 26, 1934, Serial No. 754,726

7 Claims. (Cl. 308—180)

This invention relates to journal box constructions, particularly to roller bearing journal box constructions for railway car axles. The invention has for its principal object to provide a simple, economical and efficient roller bearing journal box construction of the above type which is strong and durable, compact enough for use with narrow truck pedestals and capable of ready disassembly for inspection purposes. The invention consists in a roller bearing journal box construction comprising two outer roller bearing raceway members, a spacing member therefor and two end closure members that are rigidly secured together end to end to form the journal box; and it also consists in the parts and combinations and arrangements of parts hereinafter described and claimed.

In the accompanying drawings, which form part of this specification, and wherein like symbols refer to like parts wherever they occur,

Fig. 1 is a side elevational view, showing a roller bearing journal box embodying my invention mounted on the end portion of a railway car axle,

Fig. 2 is a plan view,

Fig. 3 is an outer end view of the journal box,

Fig. 4 is a vertical central longitudinal section on the line 4—4 in Fig. 2,

Fig. 5 is a horizontal central longitudinal section on the line 5—5 of Fig. 4; and

Fig. 6 is a vertical transverse section on the line 6—6 in Fig. 4.

In the accompanying drawings, a roller bearing journal box A embodying my invention is shown mounted on a railway car axle or shaft B between the end of the axle and the wheel seat B' thereof. Said journal box or housing comprises two outer raceway members, such as the cups 1 of two axially spaced taper roller bearings, a spacing sleeve 2 located between the two cups, a cover or closure member 3 for the outer end of the outermost cup, a closure member ring 3a for the inner end of the innermost cup, and through bolts 4 extending through registering horizontal apertures provided therefor in the four corners of said cups, said sleeve and said end closure members for rigidly clamping them together in endwise abutting relation. Rabbet joints 5 are provided between the cups 1 and spacing sleeve 2 and between said cups and the respective end closures 3 and 3a, by means of interfitting annular ribs and recesses at the abutting ends thereof.

The cups 1 and spacing sleeve 2 are of rectangular shape, having flat top, bottom and sides;

and suitable liner plates 6 are attached to the side faces of the spacing sleeve flush with the sides of said cups and have their upper and lower ends bent inwardly over the respective upper and lower side corners of said spacing sleeve and welded or otherwise rigidly secured thereto. The end closure members 3 and 3a are provided at their cup engaging ends with outstanding vertical side flanges 7 and 7a, respectively, that cooperate with the outer side faces of the cups 1 and spacing member 2 to form vertical channels adapted to straddle the sides of a truck pedestal jaw (not shown).

Located on top of the cups 1 and spacing member 2 is an adapted plate 8 provided with seats 9 for supporting the ends of suitable equalizer bars (not shown) of the truck. The adapter plate 8 has its bottom surface offset upwardly between cups, as at 10, so as to relieve the spacing member 2 of the weight of the car body. The adapter plate 8 is held in place on the journal box by upstanding flanges 11 at the upper side corners of the cup spacer 2 and by upstanding flanges 12 and 12a at the upper cup opposing end corners of the end closure members 3 and 3a, respectively.

As stated above, each of the longitudinal spaced cups 2 forms the outer raceway member of a taper roller bearing. The inner raceway member of each of these taper roller bearings comprises a cone 13 that is mounted on the axle B and a series of conical bearing rollers 14 interposed between the cup and cone and held in proper spaced relation by a suitable cage 15. The innermost cone abuts against a shoulder 16 provided therefor on the axle B; and the two cones are held in proper spaced relation on said axle by a spacing ring or sleeve 17 mounted thereon.

The outer end closure 3 of the journal box A is provided with an opening closed by a screw-threaded plug 3', whereby lubricant may be supplied to the journal box and the level of the lubricant therein determined. The annular space between the axle B and the inner end of the inner closure member 3a of the journal box A is closed by means of a ring 18; and a suitable oil flinger ring 19 is mounted on the axle between said closure ring and the end of the bearing cone located adjacent thereto and is provided with an inwardly extending annular flange 20 that overlaps an annular rib 21 on said closure ring, thereby preventing the escape of lubricant from the inner end of the journal box.

By the arrangement described, the cups 1 of the two taper roller bearings, the cup spacing

member 2 and the end closure members 3 and 3a are all rigidly secured together to form a strong and durable roller bearing journal box of very simple construction, which can be readily disassembled for inspection purposes. The rabbet joints 5 between the cups, and the end closure members and the cups and the spacing member serve to hold the parts in proper endwise alignment, prevent leakage of the journal box at such joints and relieve the securing bolts of side strain. The flat sides of the cups and the spacing member therefor and the side flanges of the end closure members cooperate to form channels for the pedestal jaw of the truck; and the flat tops of the cups and spacer provide relatively large flat areas for supporting the adapter plate, which is held in position by the flanges at the upper ends of the cup spacing member and the end closure members. The cups and spacing member therefor form a built-up or sectional journal box, thus dispensing with the use of a separate housing for the bearings and making the journal box narrow enough for use with narrow frame jaws or pedestals.

Obviously, the hereinbefore described roller bearing journal box construction admits of considerable modification without departing from the invention. Therefore, I do not wish to be limited to the precise construction shown and described.

What I claim is:

1. A roller bearing journal box construction comprising two roller bearing outer raceway members, a spacing member disposed between said raceway members, closure members at the remote ends of said raceway members, and means for rigidly securing said members together in endwise alignment to form the journal box, said spacing member forming the top, bottom and sides of the journal box between said raceway members.

2. An outboard roller bearing journal box construction comprising two roller bearing outer raceway members, a spacing member disposed between said raceway members, end closure members, the outer one of which is closed, and means for removably securing said members together in endwise alignment to form the journal box, said means comprising bolts extending through registering apertures provided therefor in said members, said spacing member forming the top, bottom and sides of the journal box between said raceway members.

3. A roller bearing journal box construction comprising two roller bearing outer raceway members, a spacing member disposed between said raceway members, means for removably securing said members together in endwise alignment to form the journal box, said raceway members and said spacing member having flat sides, and wear plates covering the flat sides of said spacing member and arranged with their outer faces flush with the flat sides of said raceway members and with their ends overlapping the top and bottom of said spacing member and welded thereto along their edges.

4. An outboard roller bearing journal box construction comprising two roller bearing outer raceway members, a spacing member disposed between said raceway members, said members having flat outer side faces, and closure members 5 for the remote ends of said raceway members, the outer end closure member being closed, said raceway members and said spacing sleeve being provided with flat sides and said closure members being provided at their raceway engaging ends 10 with outstanding side flanges that cooperate with said flat sides to form channel-shaped pedestal ways at the sides of said box.

5. A roller bearing railway journal box construction comprising two flat-topped roller outer 15 bearing raceway members, a spacing member interposed between said raceway members, closure members for the remote ends of said raceway members, and means for securing said members together in endwise alignment to form the journal 20 box, the flat-topped portions of said cups constituting seats for an equalizer bar supporting plate, said spacer member being provided at its upper side corners with upstanding flanges for limiting horizontal movement of said plate cross- 25 wise of said journal box.

6. A roller bearing railway journal box construction comprising two flat-topped roller outer bearing raceway members, a spacing member interposed between said raceway members, closure 30 members for the remote ends of said raceway members, and means for securing said members together in endwise alignment to form the journal box, the flat-topped portions of said cups constituting seats for an equalizer bar supporting 35 plate, said spacer member being provided at its upper side corners with upstanding flanges for limiting horizontal movement of said plate cross- 40 wise of said journal box, said raceway and said spacing members being provided with flat outer side faces and said closure members being provided with outstanding side flanges adapted to cooperate with said flat faces to form pedestal 45 engaging channels.

7. A roller bearing railway journal box construction comprising two flat-topped roller outer bearing raceway members, a spacing member interposed between said raceway members, closure members for the remote ends of said raceway members, means for securing said members together in endwise alignment to form the journal box, the flat-topped portions of said cups constituting seats for an equalizer bar supporting plate, said spacer member being provided at its upper side corners with upstanding flanges for 50 limiting horizontal movement of said plate cross- 55 wise of said journal box, said raceway and said spacing members being provided with flat outer side faces and said closure members being provided with outstanding side flanges adapted to 60 cooperate with said flat faces to form pedestal engaging channels, and wear plates covering the flat sides of said spacing member with their outer faces flush with the flat sides of said raceway members.

HOMER L. HEXAMER.
